Willis C. Miles Inventor

UNITED STATES PATENT OFFICE.

WILLIS C. MILES, OF JERSEY CITY, NEW JERSEY.

COVER FOR EARTHEN CHAMBER VESSELS.

SPECIFICATION forming part of Letters Patent No. 752,088, dated February 16, 1904.

Application filed June 26, 1902. Serial No. 113,301. (No model.)

To all whom it may concern:

Be it known that I, WILLIS C. MILES, a citizen of the United States, residing at 545 Ocean avenue, Jersey City, in the county of Hudson, 5 State of New Jersey, have invented a new and useful Improvement in Covers for Earthen Chamber Vessels, of which the following is a specification, reference being had to the accompanying drawings, forming a part thereof,

in which—

Figure 1 illustrates an earthen chamber vessel with the cover partially broken away and the invention embodied. Fig. 2 is a vertical central section through the cover and 15 pocket, showing projections within the pocket to obstruct or prevent the contents from working out the opening. Fig. 3 is a partial section showing upright projections employed, as stated.

20 My invention consists of an improvement in earthen chambers whereby the cover employed as a closure thereto may have attached means to purify the vessels, that the offensive odors which arise when the vessel is employed in a bedroom may be abated. To accomplish this result, I mold or attach integral 25 a small pocket or receptacle upon the under side of an ordinary earthen chamber-cover—that is to say, while the vessel and cover are 30 in course of construction at the kiln the pocket is simply attached or added thereto with the possible expenditure of a cent or two and with scarcely any additional weight, and as convenient for a child to handle as for an adult, 35 and as the pocket is adapted to contain a disinfectant of a mild character, presumably camphor-gum, camphor or tar balls, or scented soap, the odor therefrom will not become offensive even in a room with little or no ventilation.

40 In the invention I do not change the mode of constructing covers from that which is in vogue to-day. The cover remains the same—a solid earthen cover with the invention embodied as in one piece.

A illustrates the body of an ordinary earthen

bedroom-chamber and the same may be in the form shown or otherwise.

B is the usual earthen cover for a bedroom-chamber and may be constructed in the form and shape shown or otherwise. Said cover may, however, be constructed of material other than that of earthen (possibly of pulp or agate-ware) to conform with the chamber for which it is made.

55

C is a small open-mouth pocket or receptacle connected to the under side of said earthen cover and preferably of the same material and formed or molded with the cover in its construction. The same may nevertheless be made 60 of such material as may be preferred and perforated, as illustrated, or woven net-like and attached as aforesaid. Still I do not confine myself to the mode of attaching shown, so long as the essentials of the invention are employed; also there are various means or ways 65 known and in use which could be employed.

D is an opening to the pocket by which it may be filled. The same may be located in the place shown or in any suitable place, and 70 as the construction as a whole is earthen no closure to said opening can conveniently be attached. Means projecting within the pocket may be set to protect the opening. An ordinary cork can be employed, if desired, as a 75 closure.

E represents upright projections which I sometimes place within the pocket as means to obstruct or prevent the contents from rolling out the pocket. It is not essential that 80 the means thus employed and for the purpose stated be in the form shown, as small blocks or ridges or flange-like partitions within the pocket will produce the same result as the upright projections. Said projections or equivalent may be placed in any preferred position 85 within the pocket, possibly around or near the opening, to prevent the contents falling out.

What I claim as my invention, and desire to secure by Letters Patent, is—

90

1. The combination, with an ordinary earthen cover for a bedroom-chamber, of a small open-

mouth pocket connected integral upon the under side of said cover, as and for the purpose specified.

2. The combination, with an ordinary earthen cover for a bedroom-chamber, of a small open-mouth pocket to contain disinfectant, attached integral upon the under side of said cover, and means set within the pocket to prevent the contents from working out of the opening.
3. In combination with an ordinary cover for a bedroom-chamber, of a small receptacle to hold disinfectant attached upon the under

side of said cover, an opening by which the same may be filled, and means connected thereto by which the contents are prevented from falling out the pocket, as set forth.

In testimony whereof I have signed my name to this specification in the presence of two subscribing witnesses.

WILLIS C. MILES.
